[57] ABSTRACT

A tuned two mass swing system including a base reaction mass and a frame feeder mass supported thereon by elastic coupling means permitting independent horizontal and vertical natural frequencies and independent horizontal and vertical components of vibration

effective to swing the feeder frame in a controlled excursionary vibratory path for feeding material. An independent horizontal vibratory exciter means and an independent vertical vibratory exciter means is required to supply the independent horizontal and vertical components of vibration. Through a control means connected to independently and variably control the exciter means enables one to adjust the magnitude of each of the horizontal and vertical components of vibration and also to independently and variably adjust the operating phase relationship between the horizontal and vertical components of vibration for the purpose of regulating the action of the material moved. This is true of a straight feeder as well as a bowl feeder. One set of flat leaf springs disposed in the horizontal plane and with their adjacent ends connected to another set of flat leaf springs disposed vertically may be employed as the elastic coupling to provide the independent horizontal and vertical natural frequencies and the independent motion resulting in the vertical and horizontal components respectively. This may also be obtained through the use of resilient material fastened on the one side to the reaction base and on the other side to the feeder frame. A single or a multiple number of elastic members may be employed to support the feeder frame when independent horizontal and vertical components are applied thereto. Thus the structure of the elastic support together with the control enables one to independently regulate the action of the material moved by the feeder means.

**TWO MASS SWING SYSTEM WITH
INDEPENDENTLY CONTROLLED VIBRATORY
EXCITER MEANS**

This invention relates generally to a two mass swing system coupled by elastic means commonly employed as a material handling device and more particularly to the apparatus and method for variable adjustment of the vibratory components of force imposed upon the system to effect a change in the magnitude of the vibratory components of force and in the phase relation between such vibratory components of force to produce a change in the excursionary path of displacement and obtain optimum feeding action for any given feeding application.

The art of vibratory feeding devices is a well established art wherein generally a two mass system is coupled together with an elastic means such as leaf springs and set into vibratory motion with a vibratory exciter means, such as, an eccentric weight motor or electromagnetic motor mounted on one of the masses. In the latter case, a coil-wound core is secured to one mass and its armature on the other mass, so that, upon energizing the coil from an alternating or pulsating source, self-induced vibratory modes of motion are imposed upon the system.

With a given two mass system, the angle of resultant vibratory motion or feed angle of the system remains the same. This presents a problem in common practical application of such vibratory material handling devices, in that, a two mass swing system constructed for a particular feeding application is not necessarily useful in another feeding application due to differences in the materials to be handled including such considerations as the size, weight, coefficient of friction, etc. Thus particular attention is always directed to the feed angle to be designed into the system depending upon the particular feeding application. In order to apply the same material handling device to another feeding application, the feed angle of the entire system may, necessarily, therefore have to be changed. The most expedient and simplest method to vary the feed angle is to change the elastic or spring means specifications. Such a change would not only be time consuming and bring about additional expense for each change of the feed angle of the system but also limits the productive use and overall utility of such material handling devices.

The principal object of this invention is the provision of a universal two mass swing system which may be adjusted to provide optimum feeding requirements for a broad range of load conditions and feeding applications without changing or interfering with the natural frequencies of the system.

Attempts have been made in the past to provide such a universal two mass swing system but these applications always involved a simultaneous adjustment in or interfere with the natural frequency of the system. Such examples are illustrated by U.S. Pat. Nos. 3,048,260 and 3,258,111. In such systems as taught in these patents, the swing motor system incorporates an adjustable means to permit a change in the angle of resultant vibratory motion imposed upon the system in order to compensate for variable load conditions. In each of these systems the adjustment made to provide for an optimum feed rate also simultaneously effects the natural frequency of the system requiring additional adjustment in natural frequency. The practicality of such ad-

justments becomes impermissible in material feeding applications involving a broad range of variable load conditions.

Another object comprising this invention is the provision of a flexible, readily adaptable two mass swing system having versatile control of the vibratory components of motion imposed upon the system and thus capable of providing optimum feeding requirements over a wide range of variable load conditions eliminating inherent problems present in the prior art, such as, retuning of the whole two mass swing system, narrow limits of optimum feed adjustment present in such systems and the time required to accomplish the retuning of the system.

Another object comprising this invention is the provision of independently controlled vibratory exciter means in a two mass swing system which are independently controlled to change the phase relation of one relative to the other to produce various paths or wave shapes of motion on the masses of the system and, thus, provide variable control of the rate of feed of material to obtain the optimum feed rate for a wide range of feeding applications.

An important improvement residing in the structure comprising this invention over the prior art in ease and ability to adjust the two mass swing system for optimum feeding without making a mechanical adjustment in the two mass system, the latter which will effect the natural frequencies of the system. Rather, the operating phase relation between the exciter means is controlled in order to obtain optimum feed rates for a range of variable feeding applications without interfering with or effecting the natural frequencies of the entire two mass system.

In any two mass vibratory system, the natural frequency in one permissible plane of movement should be substantially the same as that in the other permissible plane of movement. In the feeding application of a two mass torsional swing system, the natural frequency in the vertical mode of permissible movement should be substantially the same as that in the torsional mode. In this particular vibratory system, in order to obtain the desired natural frequency of these modes, the load and mass in the vertical mode to be set into vibratory motion must be taken into consideration, while in the torsional plane, the moments of inertia must be considered in order to properly determine the proper specifications of the elastic coupling means. A principal feature comprising this invention is a control means, divorced from the mechanical aspects of the two mass system, eliminating constant consideration of the selection of elastic coupling means in the manufacture of a material handling device to obtain the desired frequency of the modes of vibration for each given set of load conditions.

Another object comprising this invention is the provision of elastic coupling means which permit independent directional modes of vibration upon excitation, which, when independently controlled, permit a wide range of control of the path of motion of the feeder frame of the material handling device. The frequency of excitation imposed upon each mode of vibration can be independently adjusted to obtain various forms of the combined pattern of movement, such as an elliptical path of variable eccentricity. Such an elastic coupling means permits flexibility in the selection of the natural frequency of each mode of vibration as well as the exciting frequency.

Another object comprising this invention is the provision of a control means to permit adjustment of the operating phase relation which is the sequence of the imposed modes of vibratory motion induced in the two mass swing system by the vibratory exciter means. Each of the exciter motor means is independently controlled through a circuit in order to change the phase relation between the horizontal mode of motion produced by one of the exciter means and the vertical mode of motion produced by the other of the exciter means in order to arrive at the desired imposed excursionary path of motion imposed on the feeder frame.

Another object comprising this invention is the provision of a phase control to compensate for the adverse effects of dampening caused by the introduction of load into the material handling device. This dampening effect causes a phase shift between the separate modes of vibration, in that, the period of vibration of the vertical mode of vibration is not in proper time sequence with the horizontal mode of vibration. Adjustment may be made with the control means impedance of the vertical mode of vibration to bring these component modes of vibration back into a proper phase relationship.

A circuit is supplied to control the excitation of the exciter means as well as vary the operating phase relationship between the horizontal and vertical components of vibration. The phase relationship may be defined as the phase sequence between the horizontal mode of motion and the vertical mode of motion. The change in phase relation is produced by changing the operating phase relationship between the applied voltage and current to one of said exciter means. An important object comprising this invention is the provision of an elastic means which permits two different directional modes of vibration, the resultant effect of the modes being imposed upon the feeder frame of the material handling device. The ability to control the different directional modes of vibration permits optimum control over the resultant vibratory pattern of motion imposed upon the feeder frame.

Another important object comprising this invention is the provision of elastic coupling means consisting of an annular elastomer. The use of this elastomer in the two mass swing system permits flexibility in the system relative to the induced vertical and horizontal modes of motion. Also the employment of an elastomer coupling means permits the complete sealing of the interior of the vibratory material handling device from dust and other foreign matter.

Another object comprising this invention is the provision of elastic coupling means in a two mass swing system consisting of jointed and symmetrically balanced horizontally and vertically disposed sets of parallel leaf springs in planes normal to one another and connected at one end to one of the masses and at the other end to the other of said masses.

Another object comprising this invention is the provision of elastic coupling means in a two mass swing system consisting of a series of elastic springs capable of flexing either horizontally or vertically and secured at one end to one of the masses and at the other end to the other of said masses.

Another object comprising this invention is the provision of independently controlled horizontal and vertical vibratory exciter means which includes a phase relation control means and amplitude control means to selectively vary the vibratory action of each of the ex-

citer means independently of the other to effect a full range of obtainable selective vibratory components of motion, the combined effect which produces a resultant vibratory motion on the masses in the two mass swing system.

Another object comprising this invention is the method of varying the phase relation of the vertical and horizontal components of vibratory forces in a vibratory material handling device without effecting the vertical and horizontal natural frequencies of the material handling device to select the optimum feed rate for a given feeding application.

Another object comprising this invention is the provision of the method of varying the direction of movement of material being fed and conveyed by a vibratory material handling device without effecting the desired natural frequencies of the vibratory handling device as well as the preselected optimum feed rate imposed thereon.

Another object comprising this invention is the provision of a method of varying the operating phase relation of vertical and horizontal feeding components of vibratory forces imposed on a feeder mass in a material handling device without affecting the natural frequencies of the device by adjusting the phase relation of the amplitude of vibration of a selected vibratory component relative to the other vibratory component while simultaneously adjusting the magnitude of one vibratory component relative to the other to obtain the optimum material feed rate imposed upon the material being moved for any given feeding application.

Another object comprising this invention is the provision of a method of controlling the path of movement of materials being moved in a material handling device without affecting the natural frequencies of the device by selectively adjusting the phase relation between the horizontal and vertical vibratory feeding components imposed upon the device by the vibratory exciter means to change the excursionary path of displacement of the feeder frame.

Other objects and advantages appear hereinafter in the following description and claims.

The accompanying drawings show for the purpose of exemplification without limiting the claims thereto, certain practical embodiments wherein:

FIG. 1 is a view in side elevation of a material handling device with parts of the housing in section.

FIG. 2 is a plan view of the material handling device of FIG. 1 with parts of the frame in section.

FIG. 3 is a sectional view in side elevation showing a modified form of the material handling device of FIG. 1.

FIG. 4 is a proportional view and side elevation of a material handling device showing a further modification of the material handling device of FIG. 1.

FIG. 5 is a sectional view in side elevation of a material handling device illustrating a novel spring structure.

FIG. 6 is a plan view of the material handling device of FIG. 5 with parts of the frame in section.

FIG. 7 is a proportional sectional view of a material handling device employing a modified elastic coupling means as compared to that illustrated in FIG. 5.

FIG. 8 illustrates a further type of elastic means for the material handling device of FIG. 5.

FIG. 9 is a view in side elevation of the material handling device showing wire spring inserts with parts of the housing in section.

FIG. 10 is a plan view of the material handling device of FIG. 9 with parts of the frame in section.

FIG. 11 is a view in side elevation of the material handling device of straight feeding design employing the elastic coupling means of FIG. 5 with parts of the frame in section.

FIG. 12 is a sectional view taken along the line 12-12 of FIG. 11.

FIG. 13 is a sectional view of a material handling device of straight feeding design employing the elastic coupling means of the material handling device of FIGS. 1 through 3.

FIG. 14 shows the electrical circuit diagram for controlling the operation of the material handling devices of FIGS. 1 through 13.

FIG. 15 is a schematic circuit diagram for controlling the operation of the horizontal and vertical motors.

Referring now to the drawings showing a two mass swing system comprising this invention and more particularly to FIGS. 1 through 4, the two mass swing system consists of a base 1 supported on isolators 2 with a frame mass 3 to which horizontal and vertical components of vibration are imparted to a feeder bowl 4, illustrated in part in the figure. The feeder bowl 4 and the frame mass 3 are coupled to the base mass by an elastic coupling means generally illustrated at 5.

As well known in the vibratory art, the base mass 1 is made preferable more massive by the addition of weight so that in the operation of the two mass swing system the rotational inertia of the base mass 1 is much larger than that of the feeder mass 3 and its accompanying feeder bowl 4. Vibratory exciter means, such as the several types illustrated in U.S. Pat No. 3,258,111, are employed to impart the necessary components of vibration to the frame mass 3 through the elastic coupling means 5. As shown in FIGS. 1 through 4, the vibratory system is set into motion by the electromagnets 6, 7 and 8.

It will be noted that everything connected with the frame mass 3 constitutes a specific mass, which, when coupled to the base 1, results in a combined inertia mass system having a specific vertical natural frequency and specific torsional natural frequency of vibration depending on the material characteristics of the elastic coupling means 5.

The base mass 1 comprises the annular support member 10, which is secured to the housing 11 utilizing the fastening bolts 19. The annular support member 10, as shown in FIG. 1, supports the elastic coupling means 5 which consists of the elastomer 12 secured between the annular elastomer support members 13 and 14. The elastomer support member 13 is supported by the annular support member 10 of the base mass 1. The inner elastic support ring 14 is secured to the cylindrical housing 15 which is part of the frame mass 3.

The upper elastic coupling means 5 consists of an elastomer 12 supported between the elastomer members 13 and 14. The upper elastomer support member 13 is secured to and supported by the housing 11 of the base mass 1 whereas the upper elastomer support ring 14 is secured to the cylindrical housing 15 adjacent to the feeder mounting plate 16 of the frame mass 3.

The feeder mounting plate 16 is provided with a support disc 17 to support the feeder bowl 4 which is secured to the mounting plate 16 by the bolt 18 received in the threaded opening 20 of the feeder bowl mounting plate 16.

The electromagnet 6 is secured to the base mass 1 by the bolt 21 and the nut 22 which supports the field core 23 on the electromagnet base plate 24. The base plate 24 is provided with the base guides 25 which are received in corresponding apertures in the base mass 1. Spring washer 26 is provided between the base mass 1 and base plate 24 to permit adjustment of the height of the field core 23 relative to its armature 27 secured, through the armature base plate 28, to the underside of the feeder bowl mounting plate 16. Upon adjustment of the nut 22 the coil base plate guides 25 aid in adjustment of the proper air gap 30 between the armature 27 and the field core 23.

As well known in the vibratory art, the electromagnet 6 consists of a field core 23 of E-shape, the central leg of which contains the coil winding 31 and the three pole faces of the field core 23 provide a uniform air gap 30 with the face of the armature 27.

The electromagnet 6 is part of the vibratory exciter means 9 and in the material handling device of FIG. 1 and imparts vertical vibratory movement through the elastic coupling means 5 to the frame mass 3. The electromagnet 6 imparts vibratory movement to the two mass vibratory system in only one mode of vibration, namely, vibrational forces along the vertical axis.

The electromagnets 7 and 8 of the vibratory exciter means 9 have the same corresponding parts as electromagnet 6. However, the electromagnets 7 and 8 comprising the rest of the vibratory exciter means 9 are employed in a horizontal plane and thus impart vibrations to the two mass vibratory system in a horizontal mode of vibration, the effect of which, in nature, is a torsional component of vibration.

Although other secondary directional modes of vibration may be born in such an exciter system, in principle, only two orthogonal components of vibration are set in motion, the compound effect of which produces a resultant excursionary path of displacement on the feeder frame 3. By independent control of the exciter means 9, the components of vibration can be controlled to variably adjust the operating phase relation between the operation of the vertically disposed electromagnet motor 6 relative to that of the horizontally disposed electromagnets 7 and 8 and also change the magnitude of the orthogonal components of vibration to permit variable selection in the degree of eccentricity of the excursionary path of displacement from that of a straight line to one of any number of elliptical shapes. The desired excursionary path of displacement to be imposed on the feeder frame is dependent upon the feeding application involved as well as the weight and size of material to be fed.

Referring to FIG. 2, the electromagnet motors 7 and 8 are secured to the indented portion 32 of the housing 11 by means of bolt 33 and nut 34. The electromagnets 7 and 8 are identical to the electromagnet 6, each having a coil winding 31 and a field core 23, the latter of which is mounted on the core base plate 35. The base plate 35 is provided with the guides 36 which are received by the apertures 37 in the indented portion 32 to permit the uniform adjustment of the air gaps 38, between the pole faces of the cores 23 and their respective armatures 27. The spring washers 26 are provided between the core base plate 35 and indented portion 32 of the housing 11 in order that the adjustment of the air gap 38 may be accomplished through the turning of the nut 34.

It will be noted from FIG. 2 that the armatures 27 are secured to the outwardly extended arms 40 of the cylindrical housing 15 through the mounting or armature base plates 41.

FIG. 3 illustrates a modified embodiment of the material handling device of FIG. 1 in that the material handling devices of FIG. 3 employs only one elastic coupling means 5. It will be noted that the elastic coupling means 5 of FIG. 1 involve concentric elastomers 12 whereas the embodiments in FIG. 3 employ one elastomer ring 42. The structure of FIG. 1 is the preferred embodiment since the use of concentric elastomer rings 12 provides a more stable two mass vibratory system as compared to the use of a single elastomer 42 shown in FIG. 3.

The elastomer 42 is supported by the elastomer support ring 13 on the housing 11 of the base mass 1 as well as being supported from the frame mass 3 by the flange member 43. The elastomer ring 42 is supported between the metal rings 44 and 45 which are positioned on the shoulder 46 of the elastomer support ring 13 and the shoulder 47 of the flange 43. The elastic coupling means 5 as shown in FIG. 3 is clamped in position by means of the bolt members 48 threaded radially relative to the central axis of the material handling device through the housing 11 against the elastomer support member 13.

The metal ring 45 may consist of aluminum whereas the metal ring 44 may consist of steel in order to reduce the massiveness of the frame mass as compared to the base mass and thus maintain larger rotational inertia in the base mass as compared to the frame mass.

FIG. 4 is another embodiment of the elastic coupling means 5 of FIG. 1 except in FIG. 4 the elastomer ring members 50 and 51 are employed as the elastic coupling means 5 between the base mass 1 and the frame mass 3. The housing 11 of the base mass 1 supports the annular clamping member 52 which secures the elastomer member 50 between the elastomer mounting plate 53 and their armature support member 54 of the frame mass 3. By the same token, the elastomer 51 is supported beneath the annular armature support member 54 on the elastomer mounting plate 55 which is secured to the base mass. Thus upon tightening of the fastening member 59 of the annular elastomer support member 52, the elastomer members 50 and 51, comprising the elastic coupling means 5, are squeezed or compressed in position, as shown in FIG. 4. Thus, the compression upon tightening support member 52 against the elastic coupling means 5 will directly alter and effect the elastic characteristics of the latter to selectively vary the natural frequencies of the two mass system.

An important difference in the elastic coupling means of FIG. 4 as compared to that shown through FIGS. 1 through 3 should be noted in the type of node set up in the elastomer. The node is that plane in cross-section of the elastomer where there is no motion in the elastomer from zero to maximum shear or compression imparted to the elastomer by the exciter means 9. In this connection, the elastomer structure shown in FIGS. 1 through 3 involve only shear components to form the node in the elastomer, whereas in the elastomer structure shown in FIG. 4, two types of components are present. In the horizontal or torsional plane there is a shear component whereas in the vertical plane there is imparted to the elastomers 50 and 51 a compression action or component.

Referring now to FIGS. 5 through 8, there is shown a two mass torsional vibratory system substantially similar to that shown in FIGS. 1 through 4 except for the elastic coupling means. The material handling device of FIG. 5 comprises a base mass 1 which supports an annular housing 11, the inner surface of which employs at periodical intervals, the mounting blocks 56. The base mass 1 supports the E-shaped field core 23 on the core base plate 24 through the mounting bolts 57. The core base plate 24 is provided with the spring washer 58 in order that adjustment to the air gap 30 may be made through the mounting bolts 57. The coil winding 31 is supported on the core 23 for electrical excitation. The armature 27 is secured to its mounting plate 28 by the mounting bolts 60 to the frame mass 3.

The elastic coupling means 5 consists of disposed sets of parallel leaf spring members 61 and 62, the former of which are disposed in the vertical direction and thus permitting a horizontal or torsional mode of vibration 20 and the latter of which are disposed in a horizontal plane and thus permitting a vertical mode of vibration. The two resilient systems or leaf spring members 61 and 62 are joined together or rigidly interconnected by the mounting block 63. The bolt members 64 clamp the ends of the spring members 61 and 62 to the rigid interconnecting mounting block 63. The central or horizontally disposed spring members 62 are centrally secured to the frame mass 3 by the bolt member 60 which also secures the armature 27 to the frame mass 3. The outer 25 ends of the vertically disposed leaf spring members 61 are secured to the mounting blocks 56. Spacers 65 may be provided to permit flexing of the spring members in the intended directional modes of vibration.

As shown in FIG. 6 the mounting blocks 56 are secured to the housing 11 by the bolt members 66, the latter of which are disposed within the intended portions 67 of the annular housing 11.

It should be noted that the means provided for adjusting the air gap 30 between the electromagnets 7 and 8 40 and their corresponding armatures 27 consists of the bolt members 68 threadably secured to the core base plates 35 which may be simultaneously threaded from the base plate 35 while threading inwardly the bolt member 70, which is threadably secured within the housing 11 in order to reduce the gap 30 between the armature 27 and the corresponding core 23. In order to make the air gaps 30 larger, the reverse procedure is done, in that, the bolt members 68 are tightened while simultaneously loosening the adjusting bolt member 50 70. It can be seen from the air gap adjustment structure of FIG. 6 as compared to the air gap adjustment of FIG. 2 that the latter employs a spring biased adjustment while the former may require more manipulation in achieving the desired air gap.

The general arrangement of the material handling device of FIG. 7 is similar to the material handling device of FIGS. 5 and 6 except in that the elastic coupling means 5 consist of a spring block member 71 having transverse slits 72 to produce a spring member 71 and solid block ends 73 and 74 with a central spring section 75 consisting of spring members having cross-sectional areas which are substantially square shape in order to permit flexing of the spring block member 71 not only in a horizontal or torsional directional mode of vibration 60 but also in a vertical directional mode of vibration. The solid block member 73 acts as a mounting block for the spring member 71 and is secured to the housing 11 of the base mass 1 whereas the mounting block 74 is

secured to the feeder bowl mounting plate 16 of the frame mass 3.

FIG. 8 shows still another modification of the elastic coupling means 5 which consists of the leaf spring members 76 each of which are twisted substantially near their ends at 77 to produce a set of vertically disposed spring sections 78 and a set of horizontally disposed spring sections 80 due to the 90° twist imposed on the spring members at the points 77. A central opening 81 is provided for receiving the horizontal disposed spring members 80 to the frame mass 3. The openings 82 are provided in the ends of the vertical disposed spring members 78 to secure the same to mounting blocks on the housing 11 of the base mass 1. Such a leaf spring structure eliminates the need of jointure blocks such as disclosed in FIG. 5 at 63.

The structure of the material handling device of FIGS. 9 and 10 is identical to that as shown in FIGS. 1 and 2 except for the elastic coupling means 5. In FIG. 9 the elastic coupling means 5 consists of wire spring members 83 radially disposed relative to the axial center of the frame mass 3 which are secured in the annular clamping members 84 and 85 to the base mass 1 and frame mass 3, respectively. The wire spring members 83 are capable of flexing in a horizontal directional mode of vibration as well as a vertical directional mode of vibration in order to permit compound vibratory motion on the feeder frame 3.

As noted in FIG. 10, the wire spring members 83 are symmetrically disposed between the base mass 1 and the frame mass 3 about the vertical axis of vibration of the material handling device. The spring clamp members 84 and 85 are provided with spaced semi-circular grooves 86 to receive the ends of the wire spring members 83 and are sufficiently smaller in diametrical size than the diameter of the wire spring members to securely hold wire spring members in position during the vibratory operation of the material handling device.

Although only one series of radially disposed and symmetrically positioned wire spring members 83 may be employed as the elastic coupling means 5 between the base mass 1 and the frame mass 2, the preferred embodiment is to employ concentrically disposed elastic spring systems as illustrated in FIG. 9 in order to obtain a more stable vibrating operation of the two mass vibratory system.

All of the foregoing examples of a versatile two mass swing system comprising this invention employ independently controlled vibratory exciter means and novel elastic coupling means in a two mass torsional pendulum swing motor system and are generally referred to as "bowl or parts feeders." However, the structures employed and methods utilized in this invention are also applicable in other types of vibratory equipment.

Referring to FIGS. 11 and 12 there is shown a vibratory feeder for straight feeding applications employing a vibratory exciter means to impart to the feeder frame independent horizontal and vertical modes of motion through elastic coupling means which permits the independent horizontal and vertical components of motion to be effective to swing the feeder frame. The feeder frame 87 represents the feeder mass and is supported on the base mass 88 through the elastic coupling means 5. The base mass 88 is supported on the isolators 90 which are attached to the brackets 91 which in turn are secured to the inside of the frame 92 of the base mass 88.

The base mass 88 also supports the U-shaped bracket 93 which supports the vibratory exciter means 9 as in the previous structures of two mass vibratory swing systems comprising this invention, the exciter means 9 comprises the electromagnets 94 and 95 which consist of the E-shaped field cores 96 having the pole faces 97. The central leg of the E-shaped field cores 96 support the coil windings 98. The electromagnets 94 and 95 are supported on their respective base plates 100 and, as shown in prior applications, are secured to the frame 93 of the base mass 88 by the bolt and nut 101. The base plates 100 are provided with the guides 102 and the spring washers 103 in order that a variable adjustment of the air gap 104 may be accomplished.

15 The armature bracket 105 is supported from the feeder frame 87 and in turn support the armatures 106 and 107 of the respective electromagnets 94 and 95. The armatures 106 and 107 are supported on the armature base plates 108 which in turn are secured to the armature bracket 105.

Upon excitation of the electromagnet 94, a horizontal component of vibration is imparted to the armature bracket 105 and feeder frame 87. On excitation of the electromagnet 95, a vertical component of vibration is imparted to the armature bracket 105 and the feeder frame 87. Through the control means employed herein, the operating phase relation and magnitudes of the components of vibration force as applied to the feeder frame 87 may be varied in order to accomplish a change in the excursionary path of motion imposed upon material being fed forward along the bottom of the feeder frame 87 and as a result obtain the optimum material feed rate for any given feeding application.

25 The elastic coupling means 5 is similar in function to that shown in FIG. 5 in that it employs horizontally and vertically disposed sets of parallel leaf springs, the ends of one set being connected to the feeder frame 87 and the ends of the other set being connected to the base mass 88. As shown in FIG. 12, vertically disposed 30 springs 110 are connected to the horizontally disposed sets of springs 111 by the U-shaped bracket 112. The coupling bracket 112 joins each independent set of leaf springs 110 and 111 at their mid-section. The ends of the leaf springs 111 are connected to the feeder frame 87 through the bracket members 113. The inside face of the base frame 92 also supports a U-shaped bracket 114 to which the ends of the vertically disposed leaf springs 110 are secured to by means of the bolts 115.

40 It will be noted in FIGS. 11 and 12 that two sets of vertically disposed leaf spring systems 110 are employed whereas only one set of horizontally disposed leaf springs 111 is employed for supporting the feeder frame 87.

45 The straight feeder structure of FIG. 13 may also employ the elastic coupling means similar to that illustrated in FIGS. 1 through 3 which employs the elastomer block members 116 which are supported on the base frame 92 by the mounting plate 117, which is supported on the isolators 90, and from the feeder frame 87 by the mounting plate 118. Due to the elasticity of the elastic mounting blocks 116, independently controlled horizontal and vertical modes of vibration may be imparted to the feeder frame 87.

50 FIG. 14 shows the control circuit diagram for controlling the vibratory exciter means 9. The vertically disposed electromagnet 6 is connected across the supply source L1 and L2. The horizontally disposed electromagnets 7 and 8 for imparting the horizontal com-

ponent of vibration to the feeder frame are connected in parallel and in turn connected in parallel with electromagnet 6. Connected in series with each of the electromagnets is a control circuit which is commonly referred to as trigger circuit employing a silicon controlled rectifier 120 having gate control circuit employing a diode 121 and 122. The diodes 121 and 122 are connected at their anodes and the cathode of the diode 121 is connected to the gate of the SCR 120 whereas the cathode of the diode 122 is connected through one line to the resistance 123 which in turn is connected to the anode of the SCR 120. Another line connects the cathode of diode 122 to the variable resistance 124. Both anodes of the diodes 121 and 122 and capacitance 125 are connected to the other side of the variable resistance 124. Capacitance 125 is connected to the cathode of the SCR 120. The variable resistance 124 permits variance in the voltage applied to the gate of the SCR 120 in order that the magnitude of the pulses supplying the vibratory exciter means may be varied.

As shown in FIG. 14 the variable impedance 126 is connected in series with the vertically disposed electromagnet 6. The adjustment of the impedance 126 varies the phase relation between the operating current and applying voltage to the vertically disposed magnet 6 which in turn effects the operating phase relation of the vertically disposed electromagnet relative to the horizontally disposed electromagnets 7 and 8. In varying the impedance 126, it may be necessary also to change the gate voltage applying to the SCR 120 in order to obtain a desired resultant excursionary path of displacement for feeding materials in the material handling device whether it be a straight line of adjustable length and inclination or an elliptical path of motion of adjustable size, eccentricity and inclination. Thus, the use of the impedance control 126 effects the magnitude of the applying voltage and, therefore, adjustment may be necessary through the variable resistance 124 to correct the applied voltage to the SCR 120. The applied voltage to the vertically disposed electromagnet 6 may be brought back to its original level in order that the desired feed action applied to the feeder frame may be obtained or the optimum feeding requirement for a given feeding application may be achieved.

The amplitude of vibration of the independently controlled horizontal and vertical exciter means may be adjusted by adjusting the resistance 124 and also provide, at any instant, correct adjustment of the feed angle of a vibratory feeder to obtain the most effective feeding action under the particular feeding conditions encountered.

The adjustment of the impedance 126 effects the phase relation between the current form and voltage form as applied to the electromagnet 6, while the same phase relation of applied current and voltage to electromagnets 7 and 8 remains constant. Thus the overall result is a change in the operating phase relation of the vertically imposed component of motion as compared to the horizontally imposed component of motion to produce different compound vibratory paths of motion of the feeder frame so that an optimum feed rate may be obtained for a given feeding application.

In connection with FIG. 14, this same control circuit may be employed with the structure shown in FIGS. 11, 12 and 13 wherein the vertically disposed electromagnet 6 of FIG. 4 would be vertically disposed electromagnet 95 and horizontally disposed electromagnets 7

and 8 would be replaced by horizontally disposed electromagnet 94.

The double pole-double throw switch 127 may be employed in electrical control circuit of the horizontal exciter means in order to change the direction of motion of the material moving along the feeder frame. The reversing of the current applied to the electromagnets 7 and 8 merely changes the phase relation of these horizontally disposed electromagnet as compared to the vertically disposed electromagnet by 180° so that the resultant compound vibratory motion applied to the feeder frame is at a feed angle of the same magnitude and inclination as the original feed angle but with an inclination in the opposite direction.

It does not matter whether the selection switch 127 is employed in the circuitry for the horizontally or vertically disposed vibratory exciter since the resultant effect in phase shift is the same.

The supply source for connection with the terminals L1 and L2 in FIG. 14 is generally of the alternating type. However, it should be realized that in order to achieve the primary object of the invention, that is, to effectively, as well as selectively, change the phase relation of the current through the vertical and horizontal electromagnet coils to produce the desired path of vibratory motion on the feeder frame. For example, one may eliminate the complete SCR control circuit from both the circuits of horizontal and vertical vibratory exciter means to obtain an alternating current through the vibratory exciter means. This would complete an AC operated two mass vibratory system wherein it would be only necessary to control each of the respective magnitudes in the separate modes with a shunt control comprising a variable auto-transformer connected in parallel with the electromagnet coils. If pulsating DC is employed a variable resistance may be connected in parallel with the respective rectifiers of the vertical and horizontal exciter means. Again, the operating phase relation of the vertical exciter means relative to the horizontal exciter means may be varied by providing the impedance 126 in series with the vertical vibratory exciter means.

Another example would be the elimination of only one SCR control circuit from one of the circuits of either the horizontal or vertical vibratory exciter means. The resultant exciting frequency would be a rectified current to one of the electromagnet coils of the vibratory exciter means and an alternating current to the other electromagnet coil of the vibratory exciter means to produce the desired motion. Thus, the SCR amplitude control would be provided for one mode of vibration and an AC shunt control, as previously explained, for the other mode of vibration with the impedance 126 for the operating phase control in either the vertical or horizontal mode of vibration.

Referring to FIG. 15, the auto-transformer 130 takes the place of the control 120 shown in FIG. 14 and their primary section is connected between lines L1 and L2 and their secondary section extends to the end of the winding whether it be straight or circular. The secondary circuit is for the vertical exciter 6 is supplied through the connection 131 to the anode of the diode 132 the cathod of which is connected by the line 133 of the exciter 6 the other end of the exciter is connected by the line 134 to the variable impedance 135. The variable connection 136 of the variable impedance 135 is connected directly to the variable connection 137 of the secondary of the auto-transformer.

The horizontal excitors 7 and 8 are connected in like manner, the line L1 is connected to the one end of the auto-transformer 138, however, the solid state semiconductor diode 140 is connected to the cross points of the reversing switch 141 one end of which is connected to the line L1 and the other side of which is connected by the line 142 to one side of each of the horizontal excitors 7 and 8. The other end of the coils of the excitors 7 and 8 are connected by the line 143 to the variable impedance 144. The variable connection 145 to the variable impedance 144 is also connected to the variable connection 146 which defines the end of the secondary of the auto-transformer. The end of the primary of the auto-transformer 138 is connected directly to line L2.

Thus to reverse the direction of operation of the feeder means one merely reverses the switch 135 in the same manner as that described with relation to the switch 127 in FIG. 14. Each of these auto-transformers are in fact the amplitude control means as set forth in the following claims and they permit one to vary either the vertical or the horizontal components through their respective exciter means 6 for the vertical and 7 and 8 for the horizontal components.

From the foregoing it is apparent that the invention herein disclosed involves control of the vibratory motion of a two mass swing system wherein several exciter means may be employed with an elastic coupling means capable of flexing in at least more than one direction to produce two independently controlled harmonic directional modes of vibration. Upon excitation of the exciter means, two independent components of vibration are imposed in the directional modes of vibration. Flexibility in the control means permits adjustment of the feed rate of material being fed in the feeder frame.

The change in feed rate may be by individual or simultaneous adjustment of the vertical and horizontal components of motion and the phase relation therebetween. Such adjustment to the vibratory components of motion produce a change in the resultant path of vibratory motion imposed upon the feeder frame. This resultant path of vibratory motion may be selected to produce the optimum feed rate for a given feeding application, whether an optimum resultant path of motion is of straight line configuration of adjustable length and inclination relative to the trough or track of the feeder frame or of elliptical path configuration of adjustable size, eccentricity and inclination.

In connection with adjustment of the horizontal and vertical components of motion, it should be noted that it is preferable to adjust only the horizontally disposed exciter means since adjustment of the vertically disposed exciter means may produce excessive bouncing or vibration. Thus the vertically disposed exciter means may be held constant at an optimum level of acceleration. The resultant effect through this preferred method of control is the most efficient feeding action in the adjustable two mass vibratory system.

I claim:

1. A tuned two mass swing system including a base serving as a reaction mass and a feeder frame serving as a feeder mass supported from the base by elastic coupling means permitting independent horizontal and vertical components of vibration to be effective to swing said feeder frame in a controlled excursionary vibratory path of displacement for feeding materials, independent horizontal vibratory exciter means and independent vertical vibratory exciter means to indepen-

dently supply said horizontal and vertical components of vibration to said feeder frame, characterized by control means connected to independently and variably control said exciter means to independently change the magnitude of each of said horizontal and said vertical components of vibration and to independently and variably adjust the operating phase relationship between said horizontal and vertical components of vibration of said vibratory exciter means to regulate the action of the material moved on said feeder frame.

5 2. The tuned two mass swing system of claim 1 characterized in that said elastic coupling means consists of symmetrically balanced horizontally and vertically disposed sets of parallel leaf springs having the adjacent 15 ends of each set rigidly interconnected and the other end of each set connected respectively to said feeder frame and to said base.

20 3. The tuned two mass swing system of claim 2 characterized in that said horizontally disposed leaf springs are connected at their opposite ends to the central portion 25 of said feeder frame to provide a linear vibration along a vertical path and the vertically disposed leaf springs are connected at their opposite end to the outer portions of said base to provide a torsional vibration about a vertical central axis.

30 4. The tuned two mass swing system of claim 1 characterized in that said elastic coupling means consists of a spring means disposed radially relative to the axial center of said feeder frame and capable of flexing horizontally and vertically and secured at one end to said feeder frame and at the other end to said base to produce a torsional vibration about a vertical central axis and a lineal vibration along a vertical path.

35 5. The tuned two mass swing system of claim 1 characterized in that said elastic coupling means consists of an elastomer means secured on one side to said feeder frame and on the other side to said base.

40 6. The tuned two mass swing system of claim 5 characterized in that said elastomer means is an annular elastomer ring means about a vertical central axis of said feeder frame and capable of flexing torsional and vertical and secured at one side to said feeder frame and at the other side to said base to produce a torsional vibration about said vertical central axis and a lineal vibration along a vertical path.

45 7. The tuned two mass swing system of claim 5 characterized in that said elastomer means consists of the plurality of annular elastomers secured in concentric arrangement about a vertical central axis of said feeder frame and capable of flexing horizontal and vertical and secured at one side to said feeder frame and at the other side to said base to produce a torsional vibration about said vertical central axis and a lineal vibration along a vertical path.

50 8. The tuned two mass swing system of claim 5 characterized in that said elastomer means are symmetrically disposed relative to said feeder frame and said base.

60 9. The tuned two mass swing system of claim 5 characterized by adjustable means to alter the elastic characteristics of said elastic means to change the horizontal and vertical natural frequencies of the two mass swing system.

65 10. The tuned two mass swing system of claim 1 characterized in that said control means includes independent switch means to reverse the phase relation of either of said horizontal or vertical components of movement relative to other to reverse the direction of resul-

tant feeding movement imposed on said feeder frame.

11. The tuned two mass swing system of claim 1 characterized in that said control means includes amplitude control means to independently and selectively vary the vibratory action of each of said vibratory exciter means to effect the full range of the relative and obtainable vibratory components of force of said horizontal and vertical vibratory exciter means alone and together with the combined resultant vibratory force imposed on said feeder frame.

12. The tuned two mass swing system of claim 1 characterized in that said control means includes magnitude control means to selectively vary the magnitude of each of said vibratory components of force of said vibratory exciter means, and variable impedance means in said control means connected to selectively adjust the phase relation between said horizontal and vertical vibratory forces of said exciter means to effect a full control range of the horizontal and the vertical components of force and the time sequence of their respective magnitudes to change said excursionary path of displacement of said feeder frame and produce the optimum feed rate and action on said feeder frame for a given material feeding application.

13. A tuned two mass swing system including a base serving as a reaction mass and a feeder frame serving as a feeder mass to which horizontal and vertical components of vibration are imparted thereto, elastic coupling means connecting said base and feeder frame to permit vibratory displacement of the latter in horizontal and vertical modes of motion to permit horizontal and vertical components of force to be cooperatively effective to swing said feeder frame in a controlled excursionary vibratory path of displacement, horizontal and vertical vibratory exciter means to independently impart said horizontal and vertical components of force to said feeder means, and control means to variably adjust the magnitudes of each component independently and the operating phase relation of said horizontal and vertical components of force of said vibratory exciter means to selectively vary the form of said excursionary vibratory path of displacement to control the action of the material moved on said feeder frame.

14. In a circuit for independently controlling the horizontal and vertical components of vibration in a tuned two mass swing system comprising a vibratory exciter means connected to supply a vertical component of vibration to said two mass swing system and supplied by a free alternating current source, a second exciter means connected in parallel to said vertical vibratory exciter means to supply a horizontal component of vibration to said two mass swing system, an amplitude control means connected in series with each of said horizontal vibratory exciter means, and variable impedance connected in series with said vertical vibratory exciter means to variably adjust the operating phase relation between said vertical and horizontal components of vibration produced by said vibratory exciter means.

15. The control circuit of claim 14 characterized by a variable impedance connected in series with said horizontal vibratory exciter means.

16. The control circuit of claim 14 characterized in that said amplitude control means is an auto-transformer connected in parallel with each of said vibratory exciter means.

17. The control circuit of claim 14 characterized in that said amplitude control means includes a gate controlled semi-conductor rectifier having its anode and

cathode connected in series with said vibratory exciter means, and gate controlled circuit connected in parallel with a variable impedance means.

18. The control circuit of claim 17 characterized in that said amplitude control means is connected in series with only one of said vibratory exciter means to provide different exciter frequencies to each of said vibratory exciter means.

19. The control circuit of claim 14 characterized by said switch means to reverse the connection of said amplitude control means to either of said vibratory exciter means.

20. The control circuit of claim 19 characterized in that said switch means is a double pole-double throw switch.

21. The circuit of claim 14 characterized in that said variable impedance includes a variable resistance in series with a wound electromagnet coil of said vertical vibratory exciter means.

22. In a vibratory material handling device, the method of independently varying the amplitude of vertical and horizontal components of vibration without effecting the horizontal and vertical natural frequencies of the vibratory material handling device comprising the steps of supporting the device for independent horizontal and vertical vibratory movement, independently regulating the horizontal and vertical vibratory feeding components of the material handling device to adjust the movement of the specific material therein,

25 and independently regulating the amplitude of vibration of the independent horizontal and the independent vertical vibratory components to select the optimum material feed rate and selected action of the material in the device.

23. In a vibratory material handling device, the method of controlling the path of movement of materials in the device without effecting the horizontal and vertical natural frequencies of the vibratory material handling device comprising the steps of supporting the

30 device for independent horizontal and vertical vibratory movement, independently regulating the horizontal and vertical vibratory feeding components to the material handling device to adjust the movement of the material therein, and independently regulating the 40 phase relation of the horizontal and vertical vibratory components to change the excursionary path of motion imposed upon the material in the device.

24. In a vibratory material handling device, the method of varying the operating phase relation of vertical and horizontal components of vibration without effecting the horizontal and vertical natural frequencies of the device comprising the steps of supporting the

45 device for independent horizontal and vertical vibratory movement, independently regulating the horizontal and vertical vibratory feeding components of the material handling device, and regulating the phase relation of the amplitude of vibration of a selected vibratory component relative to the other vibratory component while simultaneously regulating the magnitude of one

50 vibratory component relative to the other to obtain the optimum material feed rate and determine the action on the material in the device for any given feeding application.

25. In a vibratory material handling device, the 55 method of varying the direction of the path of movement of the material in the device comprising the steps of supporting the device for independent horizontal and vertical vibratory movement, providing controlled

current impulses to impart independent regulated horizontal and vertical vibratory components to the device, and changing the phase sequence of the current impulses of the selected horizontal and vertical vibratory component to change the direction of the path of movement and action of the material in the device.

26. A vibratory electromagnetic drive for imparting torsional and axial vibrations to a working member used to convey materials for vibration, said drive comprising: a base with shock-absorbers; a traverse; a common intermediate rigid member, resilient means connecting said rigid member to said base and to said traverse so as to form two resilient systems, one of which is supported by said base, and the other by said traverse, one of said systems including means enabling torsional vibrations and being stiff with respect to force applied along the longitudinal axis and yieldable to a torque acting on said axis, the other resilient system including means enabling axial vibrations and being stiff with respect to the torque applied to said longitudinal axis and yieldable to force directed along said axis; and a pair of electromagnetic exciter means, each being coupled to a respective resilient system to impart torsional and axial vibrations to a working member connected to said traverse.

27. A vibratory electromagnetic drive as claimed in claim 26, wherein said electromagnetic exciter means

respectively comprises an individual means for controlling the amplitude of its magnetic flux, thereby providing control over the amplitude of the torsional and axial vibrations respectively.

5 28. A vibratory electromagnetic drive as claimed in claim 26, wherein at least one of the electromagnetic exciter means comprises means for controlling the relative phase shift of the magnetic fluxes induced by the electromagnetic exciter means to control the relative phase shift between the torsional and axial vibrations.

10 29. A tuned two mass feeder system including a base serving as a reaction mass and a feeder serving as a feeder mass supported from said base by elastic coupling means permitting independent axial and torsional components of vibration effective to swing said feeder about a rotary central axis for feeding materials, independent axial vibratory exciter means and independent torsional vibratory exciter means to independently and respectively supply said axial and said torsional components of vibration to said feeder.

15 25 30. The two mass feeder system of claim 29 characterized in that said elastic coupling means consists of rigidly interconnected ends of independent axial and torsional resilient springs, the other ends of said independent springs connected respectively to said feeder frame and to said base.
